DESIGN FOR A HAIR CURLER

Anne Lee Wyatt, Los Angeles, Calif.

Application January 28, 1941, Serial No. 98,456

Term of patent 7 years

To all whom it may concern:

Be it known that I, Anne Lee Wyatt, a citizen of the United States of America, residing at Los Angeles, in the county of Los Angeles, State of California, have invented a new, original, and ornamental Design for a Hair Curler, of which the following is a specification, reference being had to the accompanying drawing, forming a part thereof.

In the drawing:

The lining of the drawing indicates a contrasting colored appearance.

I claim:

The ornamental design for a hair curler, as shown and described.

ANNE LEE WYATT.
